UNITED STATES PATENT OFFICE

GEORGE WATSON, OF BEACONSFIELD, BRITISH COLUMBIA, CANADA

LOCKING DEVICE

Application filed October 22, 1928. Serial No. 314,252.

This invention relates to improvements in locking devices as applied to safes, lockers, cupboards and rooms, and may also be used for automobile trucks, tool-rooms, and other like enclosures where it is desirable that several people have access without the necessity of carrying keys.

The object of the invention is to provide a cheap, easily manipulated, yet safe locking device for such enclosures, and one in which the combination of relative positional arrangement of the moving parts to open the lock can be easily altered by the owner from time to time without the necessity of taking the whole mechanism to pieces.

A further object is to provide a locking device which may be unlocked from inside the enclosure when required without upsetting the combination.

With such a lock the accidental shutting of the door of a strong-room while the attendant is inside, does not necessitate the waiting until a second person is sent for or arrive to manipulate the combination and open the door from the outside, as is necessary with existing combination locks.

The invention consists essentially in a pair of concentric rotating sleeves, the inner one of which is also capable of longitudinal or axial motion, which can be imparted to it by means of a knob or handle rigidly attached thereto. Secured to the inner end of this sleeve are a pair of pointed pins placed eccentrically with respect to the sleeve, and capable of causing the displacing of the lock bar when advanced axially to such a position as to engage with a pinion actuating same. These pins, however, cannot be so advanced until they penetrate through an intermediate plate or disc attached to a second sleeve concentric with the first, and pass in addition through a third plate or disc to which is secured the lock actuating pinion above referred to.

These sleeves are rotatably mounted inside

a third sleeve or cover, which is attached to the base plate of the lock. The latter is riveted or otherwise rigidly secured to the door of the enclosure and carries upon its rear or inside face the bolt mechanism consisting of a sliding bolt moving in guides and adapted by means of rack teeth to be moved by means of a spur pinion gearing therewith. This spur pinion is mounted on an extension or spindle passing through the base plate and terminating in a disc or diaphragm which is rotatably secured in the base of the third sleeve or cover.

There are thus two discs through which the pins on the central sleeve must pass before being in a position to actuate the locking bolt. Each disc has a pair of holes drilled through it corresponding in pitch and eccentricity to the pointed pins. The central sleeve and the second sleeve must each be rotated until the pins in the former and the holes in the latter are opposite the holes in the third plate or bolt actuating disc. When this condition obtains, the central sleeve can be pushed inwards, the pins passing through the aligned hole in the discs, and then a turning movement of the knob or handle causes the spur pinion to move the locking bolt so as to open the lock.

My invention is more clearly described by reference to the drawings accompanying and forming part of this specification, in which:

Figure 1 represents a front view of the lock as seen from the outside.

Figure 2 represents a side view of the same.

Figure 3 is a sectional plan taken on the line 3—3 in Fig. 1, and showing the internal construction.

Figure 4 is a part view of the inside or back of the lock and shows the locking bolt with rack, the guides for same, and the actuating pinion.

Figure 5 is a view of the plate or disc carried by the second or intermediate sleeve, showing the arrangement of holes therein.

In these views 13 represents the base plate upon which the lock is built, 14 the outer cover containing the rotatable sleeves, 15 the intermediate sleeve, and 16 the inner sleeve, carrying the hand knob 17. The front faces of the cover 14, sleeve 15 and sleeve 16 are flush when the knob 17 is not depressed or pushed in, and upon each of these faces division marks indicated by the numerals 1 to 10 12 are cut, so that when the sleeves are rotated, their relative positions are indicated by means of the division marks aforesaid.

The central sleeve 16 is shorter than the sleeve 15, but is kept up in position flush with the members 15 and 14 by means of a coil compression spring 18, which bears at one end upon the inner end of the sleeve 16 and at the other upon the back of the disc 19. The latter is secured into the end of the sleeve 15 20 and is represented separately in Figure 5.

The cover 14 is secured to the base plate 13 and has rotatably mounted within it the disc 20 secured by means of the retaining ring 21. The disc 20 is extended axially to form the 25 squared spindle 22 upon which is mounted the spur pinion 23 and, outside the cover plate 24, the turning knob 25.

Slidably mounted in guides 26 and 27 in the base plate 13 is the bolt 28, gearing with 30 the pinion 23 by means of the rack 38.

The bolt 28 is kept in the extended or locked position by means of the boxed compression spring 29, but can be secured in the "off" or retracted position after the door is opened by 35 inserting the pin 30 into the hole 31 in the guide 27, a hole being drilled in the bolt 28 which registers with the hole 31 when the bolt is in the "off" position.

The central sleeve 16 carries two cylindrical 40 pointed pins 32 projecting from its inner face. These pins are unequally distant from the centre of the sleeve 16, and are long enough to pass through the disc 19 and into the disc 20, when the sleeve 16 is fully depressed. When thus depressed the pins 32 engage the disc 20, and when the knob 17 is turned can thus rotate the pinion 23 mounted 45 upon the extension 22 of the disc 20.

The discs 19 and 20 are each drilled with 50 two "through" holes 33 and 34 corresponding to the pin centres 32, and with several "dummy" holes 35 which do not extend through, and it is only when the discs are turned so that the holes 33 and 34 in the disc 19 register with the corresponding holes in the disc 20, and that the sleeve 16 is turned so that the pins 32 also register with these holes, that the sleeve can be fully depressed, and the pins 32 then engage with the holes in 55 the disc 20 and thus are enabled to rotate the pinion 23.

The combination can be set by taking off the inside knob 25 and the cover 24, drawing the pinion 23 out of gear and setting the disc 60 20 in any position desired then rotating the

sleeve 15 by means of the projecting pins 36 until the "through" holes 33 and 34 in the disc 19 register with the corresponding "through" holes in the disc 20, then rotating the sleeve 16 until the pins 32 register with both sets of holes 33 and 34. The combination is then in the opening position and the pinion 23, the cover plate 24 and the knob 25 are then replaced and the three radially corresponding numbers on the top face of the sleeves 16, 15 and 14 underneath the indicator arrow 37 noted.

These numbers are shown at 5, 2 and 9 in Figure 1 and to open the lock the sleeves 16 and 15 must be rotated until the numbers 9 on the sleeve 16 and 2 on the sleeve 15 are opposite the number 5 of the outer ring of numbers stamped on the outer cover 14, and situated directly under the indicator 37. In this position the central knob 17 can be depressed and the pins 32 pass through the discs 19 and 20. The knob 17, if then turned, will rotate the pinion 23 and actuate the bolt 28.

The knob 25 engages with the extension 22 of the disc 20 and is situated inside of the door of the enclosure when the latter is closed up. It can be readily utilized to open the door from the inside on emergency, as by turning the knob 25 by hand the pinion 23 is caused to actuate the rack 38 and therefore the bolt 28 independently of the position or setting of the members 15 and 16.

It is also to be understood that the dials on the front faces of the members 14, 15 and 16 may be subdivided much more closely than as shown in Figure 1, each circle being divisible into one hundred or more equal parts, if desired, thus making the setting of the discs finer.

Having now fully described my invention, 105 what I claim and desire to be protected in by Letters Patent, is:

A locking device comprising, a securing bolt having a toothed rack thereon, a pinion engaging said rack, a spindle engaging said pinion and integrally extended at one end to form a circular plate whose surface is right-angled to the axis of said spindle, a base plate carrying guideways slidably engaging said bolt, a cylindrical casing secured to said base plate and adapted to revolvably receive the periphery of said circular plate, an intermediate sleeve revolvable within said casing, a second circular plate parallel to and slidable against the surface of first said circular plate and engaged revolvably with said intermediate sleeve, an inner revolvable sleeve of less length than said intermediate sleeve and provided with an external handle, said inner sleeve having cylindrical pins projecting beyond its inner face, a helical compression spring within said intermediate sleeve and abutting against said inner face and said second circular plate, both the said circular 110 115 120 125 130

plates having similar and corresponding perforations adapted to register with each other and to receive and engage the ends of said projecting pins, partial perforations on the inwardly facing surfaces of both said plates, said partial perforations being spaced apart on concentric centre lines and adapted to receive the extremities of said projecting pins, external means for rotating said intermediate sleeve and indicating means on the adjacent external end faces of said casing and said sleeves whereby their relative angular positions may be identified.

10 In testimony whereof I affix my signature.
